UNITED STATES PATENT OFFICE.

DANIEL DRAWBAUGH, OF EBERLY'S MILL, PENNSYLVANIA, ASSIGNOR TO
THE PEOPLE'S TELEPHONE COMPANY, OF NEW YORK.

TELEPHONE-TRANSMITTER.

SPECIFICATION forming part of Letters Patent No. 295,741, dated March 25, 1884.

Application filed November 12, 1883. (No model.)

To all whom it may concern:

Be it known that I, DANIEL DRAWBAUGH, of Eberly's Mill, Cumberland county, Pennsylvania, have invented a new and useful Improvement in Telephone - Transmitters, of which the following is a specification.

The invention relates more particularly to the construction and arrangement of electrodes, as herein set forth, the said electrodes consisting of a fixed piece of carbon or other suitable material rigidly attached to a support, and having an inclined face; and, second, of a cylinder of carbon or other suitable material sustained by another support and resting upon the inclined face of the fixed electrode. Either one or both of said supports may be a diaphragm or sound-receiving surface.

In the accompanying drawings, Figure 1 is a front view of the instrument with the cover and outer diaphragm removed, the cylindrical electrode being shown in place. Fig. 2 is a vertical section on the line *x x* of Fig. 1. Fig. 3 is a partial section of the cylindrical electrode. Fig. 4 is a rear view of the outer diaphragm.

Similar letters of reference indicate like parts.

A is the back board of the instrument.

30 B is the containing-case.

C and D are diaphragms arranged, respectively, upon the front and rear sides of the instrument.

E and F are covers containing central orifices to allow of access of sound-waves to the diaphragms.

It will be seen that in the form of instrument here shown I employ two diaphragms. Against one of these, C, the sound-waves directly impinge, while said waves meet the other diaphragm, D, after a reflection from the back board, A. To the rear diaphragm, D, and substantially at the center thereof, is secured a metal bracket, G, containing an electrode, H, the said electrode being inclined or having an upper inclined surface, substantially as shown in the drawings. I have obtained good results by making this electrode of carbon. Resting upon the upper inclined face of the electrode H is the cylindrical elec-

trode I. This electrode may be formed wholly of a block of carbon. I have found, however, the particular construction shown in Fig. 3 to be preferable in practice. As there represented, the said electrode consists of a 55 tube of carbon, J, filled with powdered carbon K, the ends being closed by pieces of paper or other insulating material cemented or otherwise secured in place. Entering the electrode I, and insulated from the tube J by a 60 sleeve of insulating material, Y, and having a T end embedded in the powder contained in said electrode, is a metal rod or electrode, L. The end of the rod L is loosely received in a socket-tube, M, which socket-tube is suitably secured at the center of the diaphragm C. In order to hold said socket-tube more firmly in place, I may apply to the rear side of said diaphragm a block of wood, N, in order to increase the thickness of the diaphragm; but I 70 do not limit myself to this or any other particular means of securing the diaphragm C and socket-tube M together, inasmuch as various methods of connecting these parts will readily suggest themselves. The socket-tube 75 M is of metal, and to it one of the circuit-wires is electrically connected.

The circuits in the instrument proceed as follows: from the battery to the binding-posts 1, by the wire *a* to the primary of the 80 induction-coil O, and thence by the wire *b* to the metal bracket G, to the electrode H, to the electrode I, to the socket-tube M, and thence, by the wire *c* on the rear of the diaphragm C, Fig. 4, to the metal contact-piece 85 P, secured upon said diaphragm. When the diaphragm C is in place, the circuit continues from the contact-piece P to a spring contact-piece, Q, secured to the case, and thence by a wire, D, to a flat metal contact-piece, R. A spring contact-piece, S, is secured inside the box of the instrument, and has one end, T, bent at right angles to pass down through an opening in the bottom of said box, the contact-piece S then overlapping the contact-piece R. The circuit continues from the contact-piece R to the contact-piece S, when the same are in contact, and finally proceeds from said contact-piece S by a wire, *e*, to the binding-post 2, and thence back to the battery. 100

The secondary of the induction-coil proceeds by wires *f* to the line binding-posts 3 and 4. From said wires *f* extend branch wires *g g* to the binding-posts 5 and 6, to which binding-post a receiving-instrument may be connected.

To the back board of the instrument, and below the arm *T* of the contact-piece *S*, is secured an arm, *U*, to receive the ring of the receiving-instrument when the same is not in use, the said ring then lifting the piece *S* out of contact with the piece *R*, and so breaking the primary circuit of the instrument.

In the form of telephone here shown, where two diaphragms are employed, I interpose between the back board and the box or case of the instrument blocks *V*, so as to leave an air-space between the rear diaphragm and the back board, *A*, into which sound-waves may enter. I find it preferable to secure the induction-coil *O* directly to the back board, *A*, and to make an opening in the diaphragm *G* to receive it. In order to prevent displacement of the induction-coil, I provide a bar, *W*, and to prevent the electrode from becoming displaced I arrange above it an arm, *X*, the under side of which arm is covered with paper or other insulating material.

The operation of the instrument is as follows: The sound-waves produced by the voice impinge directly upon diaphragm *C*, and after a reflection from the back board, *A*, also upon the diaphragm *D*. These diaphragms are therefore both set in vibration, and communicate their motions to the electrodes *H I*, thus causing the same to produce modifications in the current passing through them.

I do not limit myself to a telephone containing the electrodes, as described, in combination with two diaphragms, inasmuch as I may suppress the diaphragm *B* and back cover, *F*, altogether, and cause the metal bracket *G* and electrode *H* to be sustained by the back board, *A*, or any other suitable support.

I claim as my invention—

1. An electrode for telephone-transmitters, composed of an envelope of carbon or other conductor containing a mass or body of finely-divided conducting material, substantially as described.

2. An electrode for telephone-transmitters, consisting of an envelope of carbon or other similar conducting material containing a mass of finely-divided conducting material, and an electrode penetrating the envelope and insulated therefrom, and embedded in the finely-divided material, substantially as described.

3. An electrode for telephone-transmitters, composed of a tubular shell of carbon or other similar conducting material, closed at both ends, and containing a mass of finely-divided conducting material, substantially as described.

4. An electrode for telephone-transmitters,

composed of a tubular shell of carbon or similar conducting material, closed at both ends, 65 and containing a mass of finely-divided conducting material, in combination with an electrode passing through said shell and insulated therefrom, and embedded in the finely-divided conductor, substantially as described. 70

5. In a telephone, a diaphragm or sound-receiving surface, an electrode having an inclined upper surface, a second electrode consisting of a shell of conducting material containing finely-divided conducting material, 75 and a third electrode embedded in said finely-divided material and insulated from the shell, and having its end loosely connected to the diaphragm, substantially as described.

6. In a telephone, a diaphragm, an electrode of cylindrical form loosely connected to said diaphragm, and a fixed electrode having an inclined upper surface, the loose electrode resting upon said surface by gravity, substantially as described. 80

7. The combination of the diaphragm *C*, socket-tube *M*, rod-electrode *I*, cylindrical electrode *J K*, inclined fixed electrode *H*, and a support for said last-mentioned electrode, 85 substantially as described. 90

8. In a telephone, a diaphragm, a support, and three electrodes, one electrode having an inclined upper surface and rigidly attached to the support, the second electrode resting upon the inclined electrode by gravity, and 95 containing conducting material in a finely-divided state, and the third electrode having one end embedded in said finely-divided material and the other end loosely connected to the diaphragm, substantially as described. 100

9. In a telephone, two diaphragms and three electrodes, one electrode having an inclined upper surface and rigidly attached to one of the diaphragms, the second electrode resting upon the inclined electrode by gravity, and 105 containing conducting material in a finely-divided state, and the third electrode having one end embedded in said finely-divided material and the other end loosely connected to the other diaphragm, substantially as described. 110

10. In a telephone, in combination with the vibratory diaphragm and a rear support carrying a block of conducting material, the compound electrode consisting of a metallic conductor embedded in a finely-divided conductor, which latter is inclosed in an envelope of carbon or similar conducting material, said compound electrode being supported at one end upon the fixed electrode and at the other 115 in loose metallic contact with the diaphragm, substantially as described. 120

DANIEL DRAWBAUGH.
